(Continued)*Primary Examiner* — David G Muller(74) *Attorney, Agent, or Firm* — Stoel Rives LLP(57) **CLAIM**

The ornamental design for a high pressure mechanically assisted device handle, as shown and described.

DESCRIPTION

FIG. 1 is a perspective view of a high pressure mechanically assisted device handle, lined for the colors green and gray. FIG. 2 is a second perspective view thereof.

FIG. 3 is a front view thereof.

FIG. 4 is a back view thereof.

FIG. 5 is a left side view thereof.

FIG. 6 is a right side view thereof.

FIG. 7 is a top view thereof; and,

FIG. 8 is a bottom view thereof.

The broken line showing parts of the drawings is included for the purpose of illustrating use and environment and forms no part of the claimed design.

1 Claim, 6 Drawing Sheets(56)
